(57) **CLAIM**

The ornamental design for a portable baking oven as shown and described.

DESCRIPTION

FIG. 1 is an isometric view, taken from the top right front perspective, of the portable baking oven.

FIG. 2 is a front view of the portable baking oven.

FIG. 3 is a rear view of the portable baking oven.

FIG. 4 is a top view of the portable baking oven.

FIG. 5 is a bottom view of the portable baking oven.

FIG. 6 is a left side view of the portable baking oven; and,

FIG. 7 is a right side view of the portable baking oven.

The broken lines show portions of the portable baking oven

and form no part of the claimed design.

1 Claim, 7 Drawing Sheets
